UNITED STATES PATENT OFFICE.

JOHN H. HERSHBERGER, OF WILKES-BARRE, PENNSYLVANIA.

CALK-FASTENER.

1,072,006.

Specification of Letters Patent.

Patented Sept. 2, 1913.

Application filed February 28, 1913. Serial No. 751,835.

To all whom it may concern:

Be it known that I, JOHN H. HERSHBERGER, a citizen of the United States, residing at Wilkes-Barre, in the county of

5 Luzerne and State of Pennsylvania, have invented certain new and useful Improvements in Calk-Fasteners; and I do declare the following to be a full, clear, and exact description of the invention, such as will 10 enable others skilled in the art to which it appertains to make and use the same.

This invention relates to farriery, and more especially to horeshoe calks; and the object of the same is to produce an improved 15 fastener for holding the calk detachably on the shoe in such manner that it is hardly possible for it to be come accidentally detached.

This object is carried out by constructing 20 the device in the manner hereinafter more fully described and claimed, and as shown in the drawings wherein—

Figure 1 is a perspective view of a horse-shoe inverted, showing it as provided with 25 calks held in place by my improved fastener. Fig. 2 is an enlarged section through one end of the horseshoe, taken on about the line 2—2 of Fig. 1. Fig. 3 is a perspective detail of the calk in its preferred form, and 30 Fig. 4 is a perspective detail of the locking plate in its preferred form and reversed end for end in order to show its corrugations. Fig. 5 is a longitudinal section of a slightly modified form of fastener, and Fig. 6 is a 35 cross section on the line 6—6 thereof. Fig. 7 is a perspective detail of the calk employed with this form of fastener.

The horseshoe S and calk C which it is 40 the purpose of the present fastener to connect may be of any suitable material and construction so long as they possess the details hereinafter referred to.

I will say at this point that I am describing 45 in this specification the calk and its fastener at one heel-end of the shoe S; the same device will doubtless be duplicated at the other heel-end, and in the finished shoe it is probable that a double-length calk and fastener will be employed at the toe of 50 the shoe if it is desired that the calk at that point be removable. In fact, any calk may be longer or shorter than shown herein.

As the toe-calk will be merely an amplification of the one herein described, I will 55 not refer to it again. I will say further

that in all the views the shoe is reversed so that we are looking at its lower side, but in use the calks will of course project downward.

Across the lower face of the shoe is 60 formed a rib 1 whose front or inner face is undercut as at 2, and near the same a second rib 3 whose inner face 4 is beveled—the angle of the undercut face 2 being by preference greater than the angle of the 65 beveled face 4 as seen in Fig. 2. The active edge of the calk C may be of any suitable construction, but its body 5 is substantially triangular. That is to say, it has a flat upper end 6 adapted to rest normally against 70 the flat bottom 7 of the groove or space which extends across the shoe between its two ribs; its rear face 8 is beveled to correspond with the inner face 2 of the rib 1, and its front or inner face 9 is beveled to 75 preferably about the same angle as the bevel of the inner face 4 of the rib 3, which angle is by preference not as steep as the angle of the inner face 2 of the rib 1.

Coacting with the parts thus far described 80 is a locking plate 10 best illustrated in detail in Fig. 4, its body being of a length equal to the width of the shoe at this point, of a thickness slightly less than the depth of the groove formed between the two ribs, 85 and of a width to fill the space between the inner rib 3 and the inner face of the calk C. For this purpose its front edge 11 is beveled to correspond with the bevel of the inner face 4, and its rear edge 12 is beveled to correspond with the inner face 9 of the calk. The plate is provided with a hole 13, and a set bolt 14 passes loosely through the same and is threaded into the shoe S as shown at 15. It is obvious that when the 90 parts are assembled and this bolt is tightened up, the wedge shape of the plate which results from the convergence of the edges 11 and 12 will cause it to press the calk C both rearward into the angle under the rib 100 1 and upward against the bottom of the groove 7; and the fact that the plate is not as thick as the depth of said groove permits the former to be drawn upward into it without touching the bottom of the groove as 105 seen in Fig. 2.

In my preferred form of the device illustrated best in Figs. 2, 3 and 4, I provide the front face 9 of the calk C with a series of upright corrugations 16 and the rear edge 12 110

2
of the plate 10 with similar corrugations 17 excepting that those in the plate must extend throughout the entire height of its edge whereas those in the calk may run out to nothing at their lower ends as shown in Fig. 3. The purpose of this detail is to prevent the possibility of lateral dislocation of the parts, for it is quite obvious that the calk cannot move in line with its own length and 10 transversely of the shoe so long as its corrugations 16 engage those in the edge of the plate.

In the modified form of my invention shown in Figs. 5, 6, and 7 the corrugations 15 are done away with and I provide a pin 18 projecting from the base of the calk and entering a socket 19 which is formed at a proper point in the bottom of the groove 7. The meeting faces of the calk and plate in 20 this instance will be smooth as the corrugations are no longer required. I have made use of Fig. 5 to show that it is possible to have the inner face 20 of the rib 3 undercut like the inner face 2 of the other rib 1, but 25 not to as great an angle as that of the adjacent face of the calk. The result of this construction is that when the parts are in place and the set bolt tightened up, it will draw the plate upward into the groove and 30 wedge it between said face 20 and the front face 9 of the calk. However, I prefer the beveled face 4 best seen in Fig. 2, whether the corrugations are employed or not.

The parts are obviously of the desired 35 metals and proportions, and such changes in details may be made as are not inconsistent with the following claims.

When it is desired to withdraw the calk, the set bolt is loosened so that the locking 40 plate may be dropped sufficiently to disengage its corrugations from those in the calk, and the latter can then be drawn longitudinally out of place. With the form shown in Fig. 5, the set bolt must be loosened to a 45 greater extent, because the calk in this construction will have to be moved first downward until the pin 18 disengages the socket 19, after which it can be moved longitudinally out of the groove. Of course the locking plate can be entirely withdrawn if 50 preferred, and probably that course will be fol-

lowed in order to clean all parts. On restoring the calk the operation is reversed.

What is claimed as new is:

1. In a calk fastener, the combination with 55 the shoe having across its lower face a transverse groove, one wall of the groove being undercut, and a calk whose body has both side faces beveled and one of them engaging said undercut wall when the upper end of 60 the calk rests on the bottom of said groove; of a locking plate of less thickness than the depth of said groove in the shoe, its inner edge being beveled to correspond with the bevel of the other face of said calk and its 65 body having a hole, means for holding the calk from lateral dislocation when engaged by the plate, and a set bolt passing through the latter and into the shoe.

2. In a calk fastener, the combination with 70 the shoe having across its lower face a transverse groove whose rear wall is undercut and whose front wall is beveled, and a calk whose body has upwardly diverging side faces one of which is adapted to engage the undercut 75 wall of said groove and the other of which is corrugated; of a locking plate of less thickness than the depth of said groove in the shoe, its edges converging upward and adapted to fit between the calk and the front 80 wall of said groove and its rear edge having upright corrugations throughout its height, and means for drawing the calk upward into said groove.

3. In a calk fastener, the combination with 85 the shoe having across its lower face a groove, one wall of which is undercut; of a calk whose body is disposed in said groove, a locking plate disposed also in the groove, 90 one of these elements being beveled to engage said undercut wall and both elements having interengaging corrugations where they contact with each other, and means for drawing the plate upward into the groove.

In testimony whereof I have hereunto set 95 my hand in presence of two subscribing witnesses.

JOHN H. HERSHBERGER.
